GAS COCK

Ervin H. Mueller, Detroit, Mich.

Application August 3, 1936, Serial No. 93,980

5 Claims. (Cl. 251—109)

This invention relates to a valve construction, and has to do particularly with the so-called gas cock useful for the control of the flow of gas to a gas burner.

5 The invention is directed particularly to a valve of the double jet variety usually employed with a burner having two fuel pipes leading to a single burner body. One outlet or jet is usually for the flow of a relatively large volume of gas for a 10 large gas flame, and the other for a relatively small gas flow for a low gas flame.

An object of the invention is to provide an improved valve construction of the two jet variety wherein the valve structure may be adjusted to 15 cut off the flow of gas through the large jet and to confine the flow to the small jet, and all the while the gas flow to the small jet is effective. In other words, the small flow jet receives gas from the time the gas is initially turned on, entirely through the range of valve movement to and through full open position for the large jet and to "off" position of the large jet. The structure is so arranged that these results can be obtained and yet the structure is of a simple nature lending 20 itself advantageously to manufacture, and one which will not clog up in use, since all the ports and passageways therein are of generous proportions.

In the accompanying drawings:

30 Fig. 1 is a general view of a valve constructed in accordance with the invention.

Fig. 2 is an enlarged cross sectional view thereof illustrating the valve in full open position.

Fig. 3 is a cross sectional view taken through 35 the valve substantially on line 3—3 of Fig. 2 showing the valve in "off" position.

Fig. 4 is a similar cross sectional view showing the valve in full "on" position.

Fig. 5 is a similar cross sectional view showing 40 the valve adjusted to simmering position with the large jet cut off and ports open to the small jet.

Fig. 6 is a perspective view of a valve member.

Fig. 7 is a sectional view taken on line 7—7 of 45 Fig. 2.

Fig. 8 is a cross sectional view similar to Fig. 3 showing a modified form.

Fig. 9 is a sectional view similar to Fig. 8 showing the valve in its initial "on" position.

50 Fig. 10 is a similar cross sectional view showing the valve in its full "on" position.

The valve comprises a body 1 having a threaded extension 2 with an inlet passageway 3, the extension to be screw threaded into a manifold 55 or other gas supply conduit or the like. The

body has a central bore of tapered form constituting a valve seat as indicated at 4. Passageways are formed in the body, one at 5 and one at 6, which extend into the bore, and these are closed by suitable plugs 7 and 8. The body has outlet extensions 9 and 10 with outlet passageways 11 and 12 therein, which connect respectively into the passageways 5 and 6. Jet caps 13 and 14 are screw threaded on to the extensions 9 and 10, one having a relatively large jet aperture 15 and the other a relatively small jet aperture 16. The extensions 9 and 10 may be equipped with aperture control needles 17 and 18.

The valve member, as illustrated in Fig. 6, has a tapered body 20 arranged to fit in the valve seat. It has an axial bore 21 therein which extends into the valve member a depth such as to lie at least in the plane of the passageways 3 and 5 which are substantially in axial alignment. The valve is provided with a slot 22, the width of which is preferably substantially equal to the diameter of the inlet passageway 3 and the passageway 5, and the length of which is preferably such as to at one time serve to fully align with and open the passageways 3 and 5, as shown in 25 Fig. 4. This may be termed a circumferential slot through a wall of the valve member.

This valve construction may be employed with a stop mechanism such as is shown in my Patent No. 2,030,150 of Feb. 11, 1936. The valve has a 30 projection 25 and, of course, a stem 26, for the reception of a handle, for operating the same, the stem extending through a cap 27. The projection 25 limits the extreme position of movements of the rotary valve member by abutting 35 stops on the valve body shown in Fig. 7. Placed over the valve body is a washer member 28 which is keyed to the cap so that it is substantially incapable of rotation relative to the body, and a coil spring 29 is disposed between the cap and the 40 washer member. This washer abuts up against a shoulder 30 on the valve member. The washer has a stop piece with a quick lift cam face 31 and a slow lift cam face 32.

When the valve is in "off" position the parts 45 are substantially as shown in Fig. 3. It will be noted that the valve member completely blocks off the inlet passageway 3. To open the valve the member is turned clockwise as Fig. 3 is viewed, and when it is turned to a position as substantially illustrated in Fig. 4, the valve is 50 in full open position. At this time gas may flow in through the passageway 3; some of the gas may flow circumferentially through the slot 22 into the passageway 5 and to the large jet. 55

Other gas flows into the bore 21, thence to the passageways 6 and 12 to the small jet. The valve member terminates short of the end of the chamber 4, thus providing a gas flow space 33 which 5 connects the bore 21 and outlet passageway 6. Now it will be noted that as the leading edge of the slot 22 begins to open with the inlet passageway 3 that the gas flow to both jets is opened simultaneously, and the opening increases until a 10 position is assumed as substantially shown in Fig. 4. At this time there will be a high flame at the burner. The valve may be further adjusted by turning the valve member further clockwise to a position substantially as illustrated in Fig. 5. 15 Here it will be noted that the valve member has a closed off passageway 5. However, all the while until the extreme position has been reached, as shown in Fig. 5, the passageway 3 is open wide to the bore 21 so that there is a full charge of 20 gas to the small jet. At this time a small or simmering flame may be present at the burner. When the valve is turned "off" gas continuously is supplied to the small jet through the range of movement of the valve member. Of course, in 25 the reverse motion of the valve member gas is supplied to the large jet and ultimately the gas supply of both jets is cut off simultaneously.

When the valve is moved from "off" position the pin of the valve member moves until it strikes 30 the quick lift cam face 31. This serves as a substantial stopping agency to the movement of the valve, and at this time the valve is substantially fully opened, as shown in Fig. 4. Additional pressure on the valve member will cause the pin 35 to shift past the washer by shifting the same against the action of the spring 29. Thus the valve is adjusted to simmering position. When it is desired to turn off the valve the pin moves easily past the washer by reason of the slow lift 40 cam face 21. Thus if desired the valve may be operated to and from closed and fully opened position, utilizing the intermediate spring pressed stop member. Additional pressure is needed to 45 get the pin past the quick lift cam face to adjust the valve to a low flame or simmering condition.

In the modified form shown in Figs. 8, 9, and 50 10, the valve body and jet arrangement and its passageways may be identical with the body heretofore described. The rotary valve member may be identical in general construction, but the arrangement and location and function of the ports are different. The reference characters on the valve body and its passageways and 55 the rotary valve member are the same, save for the circumferential slot and axial bore in the valve member. In this structure one jet, as for example, the small jet 16, connects into the outlet passageway 12 and the large jet into the passageway 11. The rotary valve member has a bore 22a and a slot 21a. In closed position the parts are substantially as shown in Fig. 8 with the valve closing off the inlet passageway 3. When the valve is turned "on", as illustrated in 60 Fig. 9, the gas is first opened to the small jet, through the slot 21a and bore 22a to the outlet 65 12. It is at this position that the pin 25 will meet the stop member 28. As additional force is applied the valve may be turned from the Fig. 9 70 position to Fig. 10. In this position the small jet is opened as will readily be appreciated, and the large jet is now open by reason of the gas flow from the passageway 3 through the circumferential slot 21a into passageway 5 and then into outlet 75 10. As the valve is turned "off" the

large jet is first shut off and then finally the small jet is closed. In this form the valve member is rotated counterclockwise as the valve is turned "on", and clockwise as the valve is turned "off".

In the preceding form the valve member is rotated clockwise as it is turned "on" and counterclockwise as it is turned "off". However, this is an optional arrangement, as the valve may be made to turn in either direction when turning "off" or "on".

It is to be particularly noted that the valve member is of a simple formation and yet this desired action is obtained in a double jet valve. The slot and bore are of generous proportions as 15 are the bores and passageways in the valve body. There are no small apertures or passageways liable to get clogged within the valve body. The flow of gas is controlled by the small jet rather than by the employment of small apertures or 20 passageways in one or both of the valve members.

I claim:

1. A valve for gas or the like having two outlet jets comprising, a valve body having a chamber constituting a valve seat, and a gas inlet 25 passageway leading to the chamber, a valve member rotatable on the valve seat, said valve body having one outlet passageway for one jet which connects into the chamber and having a second outlet passageway for the other jet which connects into the said chamber, the valve member having an axial bore therein connecting into the chamber and the second outlet passageway, and having a single slot extending through the wall 30 and into the bore, said slot adapted upon rotation of the valve member to uncover the inlet passageway and to connect the inlet passageway and the first outlet passageway for the passage of gas from the inlet passageway to the first outlet independently of the axial bore and to 35 simultaneously open the valve to both jets, said slot having a circumferential extent such that upon further rotation of the valve member the first outlet passageway may be closed while the inlet passageway remains opened by the slot for 40 flow of gas to the second outlet passageway.

2. A valve for gas or the like having two outlet jets comprising, a body having a chamber therein constituting a valve seat and having a gas inlet 50 passageway leading to the chamber, a valve member rotatable on the valve seat, said valve member when on said seat terminating short of the end wall of the chamber to provide a gas passage space, said valve body having one outlet passageway for one jet connecting into the chamber at a point intermediate of the valve member, and a second outlet passageway for the other jet connecting into the chamber at the location of said space, the valve member having an axial bore therein connecting into said space, the valve 55 member also having a slot extending through its wall and into the bore and located in alignment with the inlet passageway and first mentioned outlet passageway, said slot adapted to uncover the inlet passageway upon rotation of the valve member and to circumferentially connect the inlet passageway and first mentioned outlet passageway and to simultaneously connect the inlet passageway and second mentioned outlet passageway through the means of said bore and 60 space, said slot having a circumferential extent such that upon further rotation of the valve member the first mentioned outlet passageway is closed while the inlet passageway remains opened 65 by the slot for the continuation of flow of gas 70 75 75

through the bore and second outlet passageway and the jet therefor.

3. A valve for gas or the like having two outlet jets comprising, a body having a chamber therein constituting a valve seat and having a gas inlet passageway leading to the chamber, a valve member rotatable on the valve seat, said valve member when on said seat terminating short of the end wall of the chamber to provide a gas passage space, said valve body having one outlet passageway for one jet connecting into the chamber at a point intermediate of the valve member, said inlet passageway connecting into the chamber in substantial axial alignment with said outlet passageway, and a second outlet passageway for the other jet connecting into the chamber at the location of said space, the valve member having an axial bore therein connecting into said space, the valve member also having a single slot extending through its wall and into the bore and located in alignment with the inlet passageway and first mentioned outlet passageway, said slot adapted to uncover the inlet passageway upon rotation of the valve member and to circumferentially connect the inlet passageway and first mentioned outlet passageway and to simultaneously connect the inlet passageway and second mentioned outlet passageway through the means of said bore, said slot having a circumferential extent such that upon further rotation of the valve member the first outlet passageway is closed while the inlet passageway remains opened by the slot for the continuation of flow of gas through the bore, second outlet passageway and the jet therefor.

4. A valve for gas or the like having two outlet jets comprising, a body having a chamber constituting a valve seat and having a gas inlet passageway connecting into the chamber intermediate its ends, a valve member rotatable on the seat, the end of which terminates short of the end of the chamber to provide a gas passageway space, said valve having one outlet passageway for one jet connecting into the chamber in substantial axial alignment with the inlet passageway and disposed substantially at right angles to the inlet passageway, and having a second outlet pas-

sageway for the other jet connecting into the chamber at the location of said space, the valve member having an axial bore therein connecting into said space and having a circumferential slot extending through its wall and into the bore and in substantial axial alignment with the inlet passageway and first mentioned outlet passageway, said slot adapted to uncover the inlet passageway upon rotation of the valve member and to circumferentially connect the inlet passageway and the first outlet passageway and to simultaneously connect the inlet passageway with the second outlet passageway through the means of said bore and space, said slot having a circumferential extent such that upon further rotation of the valve member the first outlet passageway is closed while the inlet passageway remains opened by the slot for continued flow of gas through the valve to the second mentioned outlet passageway.

5. A valve for gas or the like having two outlet jets comprising, a valve body having a chamber constituting a valve seat, a gas inlet passageway leading to the chamber, a valve member rotatable on the valve seat, said valve body having one outlet passageway for one jet which connects into the chamber intermediate its ends and having a second outlet passageway for the other jet which connects into one end of the chamber, the valve member having an axial bore therein connecting into said end of the chamber and the second outlet passageway, said valve member having a slot extending through a wall and into the bore, said slot being disposed substantially in axial alignment with the inlet passageway and first mentioned outlet passageway, said valve being turnable on the seat so that in one position it closes the inlet passageway and in another position opens the inlet passageway by means of the slot whereby gas may flow circumferentially through the slot and axially through the bore into the second outlet passageway, said slot having a circumferential extent sufficient to interconnect the inlet passageway and first mentioned outlet passageway, whereby the valve may be manipulated to open and close the first mentioned outlet passageway while the inlet passageway remains open.

ERVIN H. MUELLER.
